UNITED STATES PATENT OFFICE.

ERNST LAUSCHKE AND JULIUS SCHMOHL, OF CHICAGO, ILLINOIS, ASSIGNORS
TO THE BARNHART BROS. & SPINDLER, OF SAME PLACE.

DESIGN FOR A FONT OF TYPE.

SPECIFICATION forming part of Design No. 26,917, dated April 13, 1897.

Application filed February 20, 1897. Serial No. 624,883. Term of patent 7 years.

To all whom it may concern:

Be it known that we, ERNST LAUSCHKE and JULIUS SCHMOHL, citizens of the United States, residing at Chicago, county of Cook, and State of Illinois, have invented and produced a new and original Design for a Font of Type, which is set forth in the following specification, reference being had to the accompanying drawing, forming a part thereof.

This design comprises lower-case and upper-case letters, Arabic numerals, dollar-mark, character &, and points. In general it is characterized by a bold face, back slope, a very general angularity in the upper-case letters, which have an ornate appearance by reason of the semispiral and circumflex finials generally prevalent throughout the entire series of upper-case letters. In comparison with the upper-case letters the lower-case letters are plain, the only relief from rigid severity being found in the finials with which many of the strokes are provided, either at the upper or lower end, consisting of a rapidly-culminating acutely-pointed half-crescent seen at the lower end of the up-and-down strokes of lower-case a, b, d, f, i, j, l, and t, final strokes of lower-case h, l, m, n, and upper terminal of initial strokes of lower-case a, m, n, p, r, u, v, w, and y, and in some other analogous situations. The straight-line stems of many capitals terminate at the line in a broadly-expanded base, the expansions constituting acutely-pointed serifs of extravagant dimensions. Instances of this are seen in capitals B, D, H, K, M, N, P, and R. Capitals B and D have the expansion at the left hand only of the stem. The majority of the capital letters have a stroke which extends to the top of the letter, terminated in a horizontal circumflex acutely pointed upward at the left, as in capital B, D, E, G, H, K, M, N, P, R, and S, and a somewhat analogous characteristic acutely pointed downward at the left constitutes the cross of capital T. All other terminals of capitals (except of the horizontal cross-stroke of capital X) resemble the half-crescent terminal which characterizes the lower-case letters above de-

scribed, the crescent being, however, more extended and prominent than in the lower-case letters. Terminals of both the curved elements of capital B, both terminals of capital C, lower terminal of the curved elements of D, E, and G, lower terminal of the stems of capitals F, I, J, T, and X, terminals of the final stem of capital H and the single terminal of the cross of the same letter, upper characteristic of capital K, upper terminal of capital L and of the final stem of capital N, and the inturned terminals of the upper curves of capitals O, P, Q, R, V, and W present this characteristic.

Special characteristics pertain to individual letters. In lower case x the stroke from right to left is a strongly-marked circumflex, deriving this form from the oppositely-turned crescents at the upper and lower ends, respectively, the crescents being at each end turned inward toward the other oblique stroke of the letter. Capital A is given an appearance somewhat resembling Old English by the combination of three points at the left side, the upper one being the upwardly-pointed circumflex above mentioned as characterizing several capitals, the lower one being the upwardly-pointed semicrescent above mentioned, and the middle one being the cross-stroke produced across the left-hand stem in a downwardly-pointed crescent. Capital H approaches the same style, having the upwardly-pointed circumflex at the top of the left-hand stem and the downwardly-pointed crescent of the produced cross-stroke at the middle of the height. O and Q are rendered distinctive by the inturned and upwardly-pointed crescent, which marks one terminal of the stroke which forms the letter, the other terminal of the stroke meeting the outer convex side of the crescent and closing up the letter. The character & is an arbitrary form consisting in its principal stroke of an irregular circumflex whose general direction is oblique downward from left to right, loosely resembling the standard form of the letter S, and having appended to such stroke on the lower left-hand side, about mid-

way of the height, a short spiral which curls within the lower curve of the S-shaped stem.

We claim—

The design for a font of type herein shown 5 and described.

In testimony whereof we have hereunto set our hands, in the presence of two witnesses,

at Chicago, Illinois, this 28th day of January, 1897.

ERNST LAUSCHKE.
JULIUS SCHMOHL.
